Inventor:

Fred A. Price,

By his Attorney E. E. Masson

UNITED STATES PATENT OFFICE.

FRED A. PRICE, OF JAMESTOWN, NEW YORK.

ELECTRIC VALVE-CONTROLLER AND THERMOSTAT COMBINED.

SPECIFICATION forming part of Letters Patent No. 354,932, dated December 28, 1886.

Application filed March 25, 1886. Serial No. 196,446. (No model.)

To all whom it may concern:

Be it known that I, FRED A. PRICE, a citizen of the United States, residing at Jamestown, in the county of Chautauqua and State 5 of New York, have invented certain new and useful Improvements in Electric Valve-Controller and Thermostat Combined, of which the following is a specification, reference being had therein to the accompanying drawings.

10 The object of this invention is to automatically regulate the temperature of buildings by controlling the supply of hydrocarbon or natural gas, either in the main supply-pipe leading to the meter or in any of the rooms in 15 which this combustible is used, the whole to be operated by a thermostat and an electrical apparatus capable of adjustment to any degree. I attain this object by the mechanism illustrated in the accompanying drawings, in 20 which—

Figure 1 is a perspective view of the electrical apparatus constructed in accordance with my invention to control a valve, shown in a pipe having its side broken away. Fig. 25 2 is a side view of the thermostat used with the apparatus. Fig. 3 is a front view of the thermostat.

In the drawings, A represents the supply-pipe to convey gas from the main line to the 30 usual meter, B, or to stoves, burners, &c. The bore of the pipe A is reduced in a portion of its length, as shown at a; but said opening is yet generally slightly larger than the discharge-opening from the meter. Transversely 35 across the opening a there is a sliding valve, C, adapted to nearly close, or even close entirely, the opening a under certain conditions, hereinafter described. This valve has a stem, c, that passes through a stuffing-box, A², projecting from the under side of the pipe A, the stuffing-box being to prevent the escape of gas at that point. The lower end of the valve-stem c is screw-threaded, and is adjustably 40 connected with one end of the lever D by means of nuts c' and c'', placed upon said stem above and under the lever D. This lever is pivoted upon the ends of pointed screws e, projecting inwardly from the posts or frame E, and carries the armature D' of electro-magnets F, that 45 are isolated from the base of the frame E, although secured thereto.

The lever D extends in the rear of the arma-

ture, and the extent of its vertical oscillation is regulated by screws g and g'. The screw g passes through an arm, E², projecting from 55 the side of the frame E, and extends above the rear portion of the lever D, while the screw g' passes through the rear portion of the frame E, and is adapted to bear against the under side of the lever D. Each screw g and g' has 60 an adjusting jam-nut to retain it immovably after it is set or its point made to project the proper distance to regulate the amount of oscillation of the lever D. To the front portion of this lever, adjacent to the valve-stem, is secured one end of a coil-spring, h, the lower end of which is attached to a screw, h', projecting upward from the base of the frame E, the object of the spring h being to pull the valve C open and counteract the effect of the 70 electro-magnet.

To automatically regulate the action of this valve-controlling machine, it is connected by the wires x y with an ordinary battery and a thermostat. (Shown in Figs. 2 and 3.) The 75 latter consists of an air-tight metallic box, I, the front plate, i, of which is very thin and flexible. To this front plate is secured a bridge-piece, K, of wood or other non-conducting material, through the center of which passes 80 a screw, k, to the head of which is secured one of the wires of the battery, while the other wire is secured to the rear plate or to the body of the thermostat. The screw k is so set within its bearing in the bridge K that its point is 85 at ordinary temperature nearly in contact with the front plate, i, and any excess of temperature will cause the air in the box I to expand, force the plate i in contact with the point of the screw k, and complete the circuit, 90 causing the magnet to pull down its armature and the valve to nearly close the passage in the supply-pipe. As it is generally preferred that the gas should not be entirely shut off, but the supply be simply reduced, a small 95 opening is maintained, either by having a small groove in the end of the valve C or by suitably adjusting the nuts c' c'' upon its stem.

To set the thermostat at any desired degree of temperature and make that temperature 100 apparent upon the apparatus, the front plate, i, has a series of degrees, i', marked thereon, and the screw k has secured upon it by frictional contact a handle, k², so that the position of the

point of the screw k can be adjusted relatively to the front plate, i , independently of the handle mounted thereon and the thermostat set to any degree desired.

5 I am aware that the length of devices operating the valve of water-closet tanks and other devices has been regulated by means of nuts upon a screw-threaded rod, and I do not claim devices of this nature.

10 Having now fully described my invention, I claim—

1. In a gas-regulator, the combination of a supply-pipe, a valve-seat therein, a valve having a stem projecting from said supply-pipe, a pivoted lever having one end connected to said valve-stem and carrying an armature and controlling-screws at the other end, with an electro-magnet and a thermostat provided with an adjustable screw, k , and a

20 handle, k^2 , frictionally retained upon said screw, substantially as and for the purpose described.

2. In an automatic gas-regulator, the combination of a supply-pipe, a valve therein and connected therewith, a pivoted lever alternately controlled by a spring adjacent to said valve-stem and by an electro-magnet, with adjusting-screws bearing on said lever in the rear of said magnet, and an adjustable thermostat, substantially as and for the purpose 30 described.

In testimony whereof I affix my signature in presence of two witnesses.

FRED A. PRICE.
